CASKET

George L. West, Pittsburgh, Pa., assignor to Pittsburgh Plate Glass Company, Allegheny County, Pa., a corporation of Pennsylvania

Application May 7, 1942, Serial No. 442,051

4 Claims. (Cl. 27—3)

This invention relates to burial caskets and it has particular relation to a casket in the structure of which vitreous plates are combined with other essentially non-metallic materials.

One object of the invention is to provide an improved casket in which vitreous plate material constitutes a principal part.

Another object of the invention is to provide an improved combination of structural Carrara glass and essentially non-metallic material in the fabrication of a burial casket.

In the drawings:

Fig. 1 is a side elevation of a casket constructed according to the invention; Fig. 2 is an end elevation of the casket; Fig. 3 is a vertical section on a larger scale taken substantially along the line III—III of Fig. 1; Fig. 4 is a vertical section on a larger scale taken substantially along the line IV—IV of Fig. 2; Fig. 5 is a horizontal section on a larger scale taken substantially along the line V—V of Fig. 2; Fig. 6 is a cross section showing details of a corner construction of a casket before final assembling thereof; and Fig. 7 is a vertical section showing details of corner construction of a casket after final assembly thereof.

In practicing the invention an improved casket 10 includes a base slab 13 of wood around which wooden molding rails 14 are mounted to form a rectangular enclosing frame that is rabbeted, as indicated at 15, to receive the edges of the base slab. Upright vitreous end and side walls 16 are seated in rectangular plan inside the frame of molding rails 14 which project above the surface of the slab. These vitreous walls form joints 18 with the four sides of a horizontal rectangular plate 20 that lies flat upon the base slab 13.

A layer of asphalt mastic 21, or the like, is applied to the inside surface of the upright or horizontal vitreous plates 16 and 20 and a lining of wooden boards 23 is secured thereto. The mastic adheres firmly to the boards and to the vitreous surfaces to provide a stable composite wall structure.

Upright rails or pillars 25 extending from the frame of railings 14 are disposed at the corners and along the side walls 16 and are secured at their lower ends in the frame 14 which is provided with apertures 26 (Fig. 3) to receive such lower ends. The upper ends of these upright rails are likewise secured to horizontal rails 30 in apertures 31 formed therein. These upper rails 30 are in the form of a rectangular frame surrounding the upper portion of the casket body and such frame defines an inner shoulder 32 extending en-

tirely around and above the upper edges of the upright walls 16. A ledge 34 is thus formed of the combined upper edges of the wooden lining 23 and vitreous walls 16.

A groove 36 is formed adjacent the back of this ledge and is adapted to receive a rope of mastic 38, or other sealing material. A vitreous plate 40, for example, case-hardened or tempered glass of rectangular shape, is adapted to rest along its four marginal portions upon the ledge 34 and is provided with openings 41 disposed directly over the upper edges of the wooden board lining 23. A wooden channel structure 43 slightly wider than the ledge extends entirely around the latter and rests thereon in the form of a rectangular endless frame. This frame has a lower channel 45 facing downwardly and, as indicated in Fig. 6, the channel portion overlies at least a part of the groove 36, as well as the sealing rope 38. These elements are thus concealed by the channel frame.

Before the casket is sealed, the case-hardened plate 40 rests upon the upper side of the channel frame 43 (Fig. 6) and in this condition the casket can be shipped. After a body has been placed in the casket, the frame 43 is removed and the plate 40 is placed with its marginal portions pressing the sealing mastic into the groove 36. Suitable fastening elements, such as screws 50, each having metal and waterproof fiber washers 53 and 54, respectively, thereon, are then inserted through the openings 41 and screwed into the wooden lining 23 until the sealing mastic is pressed to fill the groove 36. The channel frame 43 is mounted upon the plate 40 with its upper side substantially flush with the upper edge of the frame 39 and with the screws and sealing mastic entirely concealed thereby.

A lid 60 for the casket is hinged, as indicated at 61, along one side of the upper frame 30. An endless wooden frame 63 constitutes the border of the lid and fits symmetrically upon the upper frame 30. A horizontal wall of boards 64 is secured in an inner lower rabbeted portion 67 of the frame and upright wooden braces 68 secured to the horizontal boards 64 partially support a top panel 69 of vitreous material, such as opaque Carrara glass which is fitted into a rabbeted portion 70 formed in the inner upper edges of the frame 63. Suitable securing means 71 maintain the top panel in place.

It is to be understood that the vitreous walls can be in the form of structural Carrara glass or other types of glass. However, it is preferable to

have the sealing plate 40 in the form of a clear case-hardened glass.

From the foregoing description it will be apparent that the casket composed of vitreous material and surrounding framework of non-metallic material provides a convenient and effective structure from the standpoint of shipping and final assembly, as well as from the standpoint of structural permanence.

Although only one form of the invention has been shown and described in detail, it will be apparent to those skilled in the art that the invention is not so limited, but that various changes can be made therein without departing from the spirit of the invention or from the scope of the appended claims.

I claim:

1. A burial casket comprising a rectangular base slab, lower rails surrounding the edges of the base slab and defining inner shoulders, a horizontal vitreous plate lying flat against the base slab, upright vitreous plates disposed against said shoulders at the ends and sides of the base slab, upper rail structure surrounding the upper edges of the upright plates to form a rectangular retaining frame for the plates, upright pillars covering the outer upright corners formed by the upright plates and connected rigidly to the upper and lower rails, and a lid having a rectangular frame hinged to the upper rail structure and including a vitreous panel surrounded by and connected to the lid frame.

2. A burial casket comprising a rectangular base slab, a lower rail surrounding the edges of the base slab and defining inner shoulders disposed around the slab, a horizontal vitreous plate lying flat upon the base slab, upright vitreous walls disposed against said shoulders at the ends

and sides of the base slab, an upper frame surrounding the upper edges of the upright walls to form an upper retaining structure for the plates and extending above the latter, upright pillars extending from the lower to the upper frame and anchored therein, and a lid including a rectangular frame hinged to the upper rail structure.

3. A burial casket comprising a rectangular base slab, lower rails surrounding the edges of the base slab and defining inner shoulders disposed around the slab, horizontal vitreous plate lying flat upon the base slab, upright vitreous walls disposed against said shoulders at the ends and sides of the base slab, an upper frame surrounding the upper edges of the upright walls to form an upper retaining structure for the plates and extending above the latter, upright pillars extending from the lower to the upper frame and anchored therein, a transparent glass plate resting upon the top of the upright walls inside the upper rail structure, and a lid including a rectangular frame hinged to the upper rail structure.

4. A rectangular burial casket comprising upright walls, a bottom of vitreous material, non-metallic horizontal frames covering the upper and lower outer corners of the casket, means for holding the frames in supporting relation to the walls, the upper edges of the walls defining a horizontal ledge, a plate of glass removably engageable upon the ledge inside the upper frame, and a frame removably engageable upon the ledge and adapted to support the latter glass plate upon said ledge, the positions of the removable frame and removable glass plate being reversible.

GEORGE L. WEST.
